CLAIM

The ornamental design for a back seat extender for dogs, as shown and described.

DESCRIPTION

FIG. 1 is a front, top and right-side perspective view of the back seat extender for dogs showing my new design; FIG. 2 is a rear, bottom and left-side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is an enlarged top plan view thereof;

FIG. 8 is an enlarged bottom plan view thereof;

FIG. 9 is an enlarged view, of circled portion 9, of FIG. 1, thereof;

FIG. 10 is an enlarged view, of circled portion 10, of FIG. 1, thereof;

FIG. 11 is an enlarged view, of circled portion 11, of FIG. 2, thereof; and,

FIG. 12 is an enlarged view, of circled portion 12, of FIG. 2, thereof.

The broken lines throughout the drawing figures depict portions of the back seat extender for dogs that form no part of the claimed design.

The dot-dash broken lines depict the boundaries of the FIGS. 1, 2 and 9-12 enlargement that forms no part of the claimed design.

1 Claim, 12 Drawing Sheets
